BAG STRINGING MACHINE

Edward E. West, Richmond, Va., and Dewey Clymer, Reidsville, N. C., assignors, by direct and mesne assignments, to said Edward E. West

Application July 25, 1930. Serial No. 470,616

20 Claims. (Cl. 112—2)

This invention has to do with bag stringing machines, the object thereof being to provide mechanism which will automatically carry a string under the hem of a continuous web of bag forming material during the folding of the hem thereof and perforate such fold to carry loops of string into position to be drawn out so as to be subsequently severed, whereby when each blank is severed from the web of material 10 to form a bag blank the string will have projecting ends which may be used to gather the top of the bag, thus obviating the necessity of stringing the bag subsequently and thereby very much facilitating the expeditious manufacture 15 of such bags and decreasing the expense of such manufacture.

As is well known, bag material in the form of a continuous web is passed through a sewing machine and during its passage one edge of the 20 material passes through a folder to form a hem, this hem being stitched by the sewing machine. The web is subsequently cut into bag blanks, each of a size to form the desired size of bag and then the string is passed through the folded 25 hem portion for the purpose of gathering the neck of the bag, a common form of such bag being a mailing bag.

This method of stringing the bags, however, is slow and expensive and the object therefore, 30 of the present invention is to automatically string the bag material simultaneously with the hemming thereof and then draw out loops of string at intervals so that when these loops are severed into bag blanks sufficient string will 35 project from the cut ends of the blank to enable the mouth of the bag to be gathered and closed when the blank is stitched into a bag, and to do this by a simple and efficient and inexpensive mechanism applicable to the ordinary hem 40 folding and stitching mechanism heretofore used for the formation of the hem of bag material.

In the drawings accompanying and forming a part of this specification

Fig. 1 is a front view of a bag hemming and 45 stitching machine having this improved stringing mechanism applied thereto.

Fig. 2 is a top view of the machine with a part of the sewing machine broken away.

Fig. 3 is a left hand end view of Fig. 1.

Fig. 4 is a detail view partly in section illustrating the means for drawing out the loops of string.

Fig. 5 is a plan view of the loop drawing out means and loop conveying means for carrying 55 the loops into position to be severed.

Similar characters of reference indicate corresponding parts in the several views.

Before explaining in detail the present improvement and mode of operation thereof, I 60 desire to have it understood that the invention

is not limited to the details of construction and arrangement of parts which are illustrated in the accompanying drawings, since the invention is capable of other embodiments, and that the phraseology which I employ is for the purpose 65 of description and not of limitation.

As the machine for stitching the web hem of bag material is of well known form, it is not deemed necessary to describe in detail the construction of this machine except insofar as it 70 has to do with the stringing mechanism and therefor, it is believed that a brief description will suffice.

The machine comprises a suitable supporting 75 means or table 2 upon which is mounted a suitable cylinder sewing machine 3 for stitching the hem, the mechanism being provided with what may be designated as a cloth plate 4 secured to the support for the passage of the web of material 80 thereover.

In the rear of the stitching mechanism is a pair of feed rollers 5 provided for drawing the material past the stitching mechanism. The sewing machine is operated by means of a belt 6 and belt wheels 7, the lower one being mounted on a shaft 8 of a suitable electric motor 9 provided with a worm gear 10 in mesh with a worm wheel 11 mounted on a shaft 12 having at its opposite end a gear 13 in mesh with an adjustably supported gear 14 carried by a bracket 15 which in turn meshes with a gear 16 mounted on the end of a cam shaft 17 for driving the cam shaft. The gear 13 meshes with a gear 18 which drives a gear 19 carried by the lower feed roll 20 thereby to rotate it, the upper feed roll 21 being adjustably held in frictional contact with the roll 20.

For the purpose of severing the web of material into bag blanks we have provided the machine at the rear of these feed rolls with a bag severing means comprising a fixed knife 22 and a rotary knife 23 timed to sever the web into the required size of bag blanks. The shaft of the rotary knife roll is provided with a gear 24 in mesh with a gear 25 which is driven by the gear 18. By this gear system the cam shaft 17, the feed rolls and knife rolls are rotated from the motor through the main driving shaft 12. Mounted on the cloth plate 4 above the sewing machine cylinder carrying the usual looper mechanism is located a hem folder 26 adjustably supported on this cloth plate. This folder is of a form to fold the hem of the continuously fed web of material which is lead from a supply roll 27 placed in front of the machine to and through the sewing machine to the feed rolls and to the cutting rolls where it is cut into bag blanks.

Mounted on a pair of guide rods 28, supported 110 on the table of the machine is a stringing needle

idle or perforator 28', this stringing needle being secured to a sliding block 28" mounted on the guide rods and this needle carries the string to be fed into the hem of the travelling web of material. For reciprocating this stringing needle a lever 29 is pivotally connected with the slide block and with an upright lever 30 pivotally mounted on the frame of the machine as at 31 and having its lower end 32 provided with a roll in position to be engaged by a cam member 33 carried on the cam shaft 17, a spring 34 holding this lever 30 in engagement with the cam member. Thus, as the cam shaft is rotated the stringing needle or perforator is reciprocated toward and from the folded hem thereby to carry the eye thereof into the hem and through the folded edge of the hem in the manner shown in Fig. 5, the string of course being drawn from a suitable supply roll.

20 As the stringing needle perforates the fold of the hem which takes place before the hem is stitched by the stitching mechanism the loop of the string is carried into position to be engaged by the loop drawing out means 35 in the form of an oscillating hook located on the upper end of a shaft 36, the lower end of which is provided with a bevel gear 37 (see Fig. 4) in mesh with a similar gear 38 mounted on the end of a horizontal shaft 39 the opposite end of which is connected with a link 40 pivotally connected to a lever 41 pivoted as at 42 to the frame of the machine and the lower end of which is provided with a cam roll 43 held in engagement by a spring 44 with a cam member 45 mounted on the cam shaft 17 and by which mechanism the hook is oscillated from the dotted position shown in Fig. 5 to carry a loop from the stringing needle into full line position where it is caught on hooks 46 of a conveyor 47 which conveys the loops into position to be severed. Thus it will be seen that as the edge of the continuously fed web of material is folded over by the folder and before it reaches the stitching mechanism the stringing perforator or needle carries the string under the hem and through the fold or folded edge thereof, forming a loop which is engaged by the loop drawing out means in the manner shown in Fig. 5, so that the string is thus laid in spaced intervals under the hem and held therein by the stitch line when this hem is stitched, this mechanism thus forming a very simple means for carrying a string into the hem and through the folded edge thereof to permit the loops of the string to be caught and carried into position to be conveyed into position to be severed, the member 35 thus drawing out a sufficient loop of string to enable it to be grasped and draw the open mouthed end of the bag together when the bag blanks have been severed from the web of material along the lines *a—a*, Fig. 5, each portion between a pair of these lines forming a bag blank which when doubled upon itself with the opposite edges thereof seamed, will form a bag.

65 It will also be observed that the stringing needle together with the loop drawing out means acts to draw the loop into and against the fold of the hem in the manner shown at *b* in Fig. 5 so that it is away from the stitch line when the hem is stitched by the sewing mechanism. When the loops carried by the conveying hooks 46 of the conveyor 47 reach the web cutting off knives these loops may also be severed by these knives which, in such case, would be sufficiently elongated to accomplish this purpose, these

knives severing the web of material along the lines *a—a* as hereinbefore stated, although of course the loops could be severed by hand if preferred. The loop conveyor may consist of a belt or chain carrying the hooks 46 located at intervals so that when the loops are drawn out by the member 35 they will be in position to be caught by the conveyor hooks 46 and carried along by the conveyor and thus prevent them from falling and interfering with the mechanism of the machine. This conveyor may be operated by any suitable means as sprocket gears or otherwise (see Fig. 4) and driven by a suitable connection with the main driving shaft.

80 From the foregoing it will be seen that each bag blank when severed from the web has a materially greater length of string than hem.

85 It is to be understood that by describing in detail herein any particular form, structure or arrangement, it is not intended to limit the invention beyond the terms of the several claims or the requirements of the prior art.

90 Having thus explained the nature of our said invention and described a way of using the same, although without attempting to set forth all of the forms in which it may be made, or all of the modes of its use, we claim:

95 1. In a bag stringing machine, the combination of means for folding a hem in a continuously fed web of material, a string carrying perforator for conveying the string under the hem and through the hem fold to form loops, means for engaging the loops and drawing out the string, and means for stitching the hem with the string therein.

100 2. In a bag stringing machine, the combination of means for folding a hem in a continuously fed web of material, a string carrying perforator for conveying the string under the hem and through the hem fold to form loops, means for engaging the loops and drawing out the string, means for stitching the hem with the string therein, and means for conveying the loops of string into position to be severed.

105 3. In a bag stringing machine, the combination of means for folding a hem in a continuously fed web of material, a string carrying perforator for conveying the string under the hem and through the hem fold to form loops, means for engaging the loops and drawing out the string, means for stitching the hem with the string therein, means for conveying the loops of string into position to be severed, and means for severing the loops.

110 4. In a bag string machine, the combination of means for folding a hem in a continuously fed web of material, a string carrying perforator for conveying the string under the hem and through the hem fold to form loops, means for engaging the loops and drawing out the string, means for stitching the hem with the string therein, means for conveying the loops of string into position to be severed, and means for severing the loops simultaneously with the severing of the web of material to form bag blanks.

115 5. In a bag stringing machine, the combination of means for folding a hem in a continuously fed web of material, means operative transversely of the direction of feed of the material for then carrying a string under the hem after the formation of such hem and through the fold thereof to form loops, means for drawing out the loops of string, means for stitching the hem with the string therein, and means for

- conveying the loops of string into position to be severed.

6. In a bag stringing machine, the combination of means for folding a hem in a continuously fed web of material, means operative transversely of the direction of feed of the material for then carrying a string under the hem after the formation of such hem and through the fold thereof to form loops, means for drawing out the loops of string, means for stitching the hem with the string therein, and means for severing the web of material into bag blanks. 80

7. In a bag stringing machine, the combination of means for folding a hem in a continuously fed web of material, means operative transversely of the direction of feed of the material for then carrying a string under the hem after the formation of such hem and through the fold thereof to form loops, means for drawing out the loops of string, means for stitching the hem with the string therein, and means for conveying the loops of string into position to be severed, and means for simultaneously severing the web of material into bag blanks. 90

8. In a bag stringing machine, the combination of means for folding a hem in a continuously fed web of material, means for then carrying a string under the hem after the formation of such hem and through the hem, means for stitching the hem with the string therein, and means for severing the web of material into bag blanks. 100

9. In a bag stringing machine, the combination of means for folding a hem in a continuously fed web of material, a string carrying perforator, means for reciprocating it thereby to carry the string under the hem and through the fold thereof to form loops, and means for stitching the hem with the string therein. 110

10. In a bag stringing machine, the combination of means for folding a hem in a continuously fed web of material, a string carrying perforator, means for reciprocating it thereby to carry the string under the hem and through the fold thereof to form loops, means for stitching the hem with the string therein, and an oscillating loop draw out means and means for oscillating it. 120

11. In a bag stringing machine, the combination of means for folding a hem in a continuously fed web of material, a string carrying perforator, means for reciprocating it thereby to carry the string under the hem and through the fold thereof to form loops, means for stitching the hem with the string therein, an oscillating loop draw out means and means for oscillating it, and means for conveying the loops into position to be severed. 130

12. In a bag stringing machine, the combination of means for folding a hem in a continuously fed web of material, a string carrying perforator, means for reciprocating it thereby to carry the string under the hem and through the fold thereof to form loops, means for stitching the hem with the string therein, an oscillating loop draw out means and means for oscillating it, means for conveying the loops into position to be severed, and means for simultaneously severing the web of material into bag blanks and the loops of string. 140

13. In a bag stringing machine, the combination of means for folding a hem in a continuously fed web of material, means operative transversely to the direction of feed of the material for carrying a string under the hem and through the fold thereof during the feeding of the material to form string loops, means operative transversely of the stringing means to engage and draw out said loops of string, and means for severing the web of material into bag blanks whereby when the loops are also severed each bag blank will have a materially greater length of string than the length of the hem. 150

14. In a bag stringing machine, the combination of means for continuously feeding a web of material, means for folding a hem in such continuously fed web of material, means for carrying a string under the previously formed hem and through the material, and means for stitching the hem with the string loose therein. 160

15. In a bag stringing machine, the combination of means for continuously feeding a web of material, means for folding a hem in such continuously fed web of material, means for carrying a string under the previously formed hem and through the web to form loops, means for drawing out the loops of string, and means for stitching the hem with the string loose therein. 170

16. In a bag stringing machine, the combination of means for continuously feeding a web of material, means for folding a hem in such continuously fed web of material, means for carrying a string under the previously formed hem and through the web to form loops, means for drawing out loops of string, means for conveying the loops of string into position to be severed, and means for stitching the hem with the string loose therein. 180

17. In a bag stringing machine, the combination of means for continuously feeding a web of material, means for folding a hem in such continuously fed web of material, an eye-formed string retaining needle operative after the folding means for conveying a string under the previously formed hem and through the material thereof, and means for stitching the hem with the string loose therein. 190

18. In a bag stringing machine, the combination of means for continuously feeding a web of material, means for folding a hem in such continuously fed web of material, means for carrying a string under the previously formed hem thereof and through the material to form loops, means for stitching the hem with the string loose therein, and loop engaging means. 200

19. In a bag stringing machine, the combination of means for continuously feeding a web of material, means for folding a hem in such continuously fed web of material, means for simultaneously perforating and carrying a string under the previously formed hem and through the fold thereof to form loops, and means for stitching the hem with the string loose therein. 210

20. In a bag stringing machine, the combination of means for continuously feeding a web of material, means for folding a hem in such continuously fed web of material, means for simultaneously perforating and carrying a string under the previously formed hem and through the fold thereof to form loops, means for drawing out the loops of string, and means for stitching the hem with the string loose therein. 220
